UNITED STATES PATENT OFFICE.

AMASA G. MILLER, OF BRISTOL, INDIANA.

FIRE-ESCAPE.

1,303,706.

Specification of Letters Patent.

Patented May 13, 1919.

Application filed April 17, 1917, Serial No. 162,684. Renewed August 28, 1918. Serial No. 251,839.

To all whom it may concern:

Be it known that I, AMASA G. MILLER, a citizen of the United States, residing at Bristol, in the county of Elkhart and State 5 of Indiana, have invented certain new and useful Improvements in Fire-Escapes, of which the following is a specification.

This invention relates to an improved fire-escape of the drum type and the principal 10 object of the invention is to provide a fire-escape having an improved type of housing for the cable drum and rewind spring and to further provide a fire-escape of the type specified in which the speed of unwinding of 15 the cable may be controlled through the medium of a brake carried by one of the handles of the drum.

Another object of the invention is to provide a fire-escape in which motion will be 20 transmitted from the shaft as the cable unwinds to the rewind spring through the medium of gears in the spring housing.

Another object of the invention is to so 25 construct this fire-escape that it may be suspended either from the roof of a building or from a ledge or other exterior projection or if so desired from within the building with the cable extending through the window.

This invention is illustrated in the accompanying drawings, wherein:—

Figure 1 is a view in elevation showing the fire-escape suspended from within the building and extending out through one of the windows.

Fig. 2 is a view similar to Fig. 1 showing the fire-escape suspended from the roof of the building.

Fig. 3 is an enlarged view showing the improved fire-escape in longitudinal section 40 with the anchor shown in elevation.

Fig. 4 is a sectional view through the spring housing taken along the line 4—4 of Fig. 3.

The cable 10 carries an anchor 11 at its 45 free end, the arms 12 of which terminate in sharp penetrating points which permit the anchor to obtain a firm grip upon a roof or other surface with which the anchor may be engaged when used as shown in Fig. 2. These

50 arms are further of sufficient length to permit the anchor to engage a beam or other object within a building when the anchor is to be engaged on a support within the room and the cable passed out of the window.

55 This anchor will be of sufficient strength to

withstand the strain when the fire-escape is in use.

This cable 10 is wound upon the hollow shaft or drum 13 within the drum housing 14 and between the disks 15, the drum housing 60 having an inlet opening 16 extending longitudinally in its upper end portion so that the cable may pass into and out of the drum housing and wind longitudinally upon the drum. The inner end of this cable is connected with the drum or hollow shaft by the fasteners 16' thus preventing the danger of the cable becoming detached from the drum. The hollow shaft or drum 13 extends through the spring housing indicated in 70 general by the numeral 17 and through the handles 18, a securing pin 19 being passed through the hollow shaft 13 to hold the shaft in place and a brake lever 20 being pivotally mounted in an opening 21 formed in one of 75 the handles so that this brake lever may be grasped and pressed against the shaft to control the speed of rotation of this shaft. These handles may be secured rigidly to the arms 22 of the yoke 23, the arms of the yoke 80 being provided with bearings 24 through which the hollow shaft passes as shown in Fig. 3.

Within the spring housing, which housing is formed of two sections 25 and 26, 85 there is provided a spring 27 having its outer end secured to the side wall of the section 25 and having its inner end secured to the hub 28 of the gear 29 which gear is rotatable upon the hollow shaft 13. A double 90 gear is rotatably mounted in the spring housing upon the pivot pin or stub shaft 30 and has its relatively small head 31 meshing with the gear 29 and its relatively large head or end portion 32 meshing with the 95 gear 33 which gear 33 is keyed to the shaft 13 as shown at 34. It will thus be seen that when the cable is drawn outwardly to rotate the shaft 13, the gear 33 constituting a driving gear will be rotated and rotary motion will be transmitted through the double gear to the loose or driven gear 28 with which the inner end of the spring 27 is connected.

When in use, the fire-escape will be put in 105 place either as shown in Fig. 1 or shown in Fig. 2 and the person who desires to descend from the upper portion of the building will grasp the handles 18 and hang from the device. The weight of the person will cause 110

the cables to unwind from between the disks and in doing so this will rotate the shaft 13 which through the medium of the gears will wind the spring 27. If the descent toward 5 the ground is too rapid, the brake lever 20 will be pressed thus bringing the brake into engagement with the rotating shaft 13 and causing the shaft 13 to rotate at a lower rate of speed. By means of this brake lever, the 10 speed at which the shaft rotates can thus be easily controlled and the person can descend to the ground at the desired rate of speed. Therefore this fire-escape does not have to be adjusted according to the weight of the 15 person who is to descend to the ground. After the person has descended to the ground, the handles 18 will be released and the spring will unwind thus rotating the shaft 13 and winding the cable upon the shaft between the disks as shown in Fig. 3. Therefore the device will be drawn upwardly so that it can again be used.

I have thus provided a fire-escape by which a person can safely descend to the ground from a window and which is so constructed that after a person has reached the ground, this device of itself will return to the upper portion of the building. ²⁵

What is claimed is:—

A fire-escape comprising a housing, a shaft ³⁰ extending through the housing, handles loose upon the shaft upon opposite sides of the housing, one of the handles having a slot formed therein, a brake pivotally mounted in the slot and having an inner arm for engaging the shaft and an outer actuating arm, and a line wound about the shaft and extending out of the housing. ³⁵

In testimony whereof I affix my signature in presence of two witnesses.

AMASA G. MILLER.

Witnesses:

HARVEY W. L. KANTZ,
AUGUSTUS ALLEN.
